A. L. POWELL

INTERNAL COMBUSTION ENGINE

Filed Feb. 2, 1921

Patented July 14, 1925.

1,545,517

UNITED STATES PATENT OFFICE.

ALVAH L. POWELL, OF MILES CITY, MONTANA, ASSIGNOR TO THE A. L. POWELL POWER CO., INC., OF MILES CITY, MONTANA, A BODY CORPORATE.

INTERNAL-COMBUSTION ENGINE.

Application filed February 2, 1921. Serial No. 441,969.

To all whom it may concern:

Be it known that I, ALVAH L. POWELL, citizen of the United States, residing at Miles City, in the county of Custer and 5 State of Montana, have invented certain new and useful Improvements in Internal-Combustion Engines, of which the following is a specification.

My invention relates to improvements in 10 internal combustion engines in which I provide a novel means of applying the power to a crank shaft on each impulse, obtaining thereby simultaneous thrusts in opposite directions, and I further provide for increasing 15 the certainty of firing and of obtaining power from charges often lost in a running engine. In the accompanying drawings—

Fig. 1 shows my improvement in an engine of the four cycle type. The view is a 20 sectional elevation.

Fig. 2 is the same, for a two cycle engine.

Figs. 3 and 4 are modifications of my improvement.

In Fig. 1 a cylinder A is mounted on stationary guide bars, A², by means of lugs A³, A⁴, which project from the walls of the cylinder A. The lugs A³, A⁴, are slidably mounted on to said bars A². In lugs A³, A⁴, are fitted pins, A⁵, which engage slides A⁶, 25 A⁶, slidably mounted on bars A², A². The cylinder A is thus made movable on said bars. On pins A⁵, A⁵, are fitted the ends of connecting rods, A⁷, A⁷, the opposite ends being fitted to cranks, A⁸, A⁸, by any conventional means. Cranks A⁸ form part of 30 a power shaft, A⁹, mounted in bearings, preferably attached to the stationary bars A², A², as shown at B.

In cylinder A there is shown a slidable 40 piston, B¹, from which a rod, B², extends to a crank, B³. The rod, B², is supported by a wrist pin, B⁴, in the piston B¹, and is attached to the crank B³ by conventional means. The crank B³ forms part of shaft 45 A⁹, but it will be noted in Fig. 1 that the crank B³ lies in the same plane with, but extends in the opposite direction from, the cranks A⁸, A⁸.

In the head of cylinder A are tubes, B⁵, 50 B⁶, in which are fitted stationary tubes B⁷, B⁸. These tubes have packing rings as shown at B⁹, Fig. 1, to insure tightness. The tubes B⁵, B⁶, are slidable in relation to tubes B⁷, B⁸. In the cylinder A, a check 55 valve, C, is fitted to control the entrance to

tube B⁵. On the upper end of B⁷ is fitted an intake valve, C¹. At a corresponding point on tube B⁸ there is an operable exhaust valve C². An ignition plug, C³, is shown in head of cylinder A. The operation of the engine is as follows:

On outstroke of piston B¹ the shaft A⁹ rotates by reason of the movement of connecting rod B². As crank B³ moves downward, cranks A⁸, A⁸, move upward. Cylinder A follows the reciprocating action of cranks A⁸, A⁸, and crank rods A⁷, A⁷, its supporting members sliding on the stationary bars A², A². Piston and cylinder therefore recede from each other on outstroke 70 and approach each other on instroke. Let it be assumed that a compressed charge is between piston B¹ and head of cylinder A, in the position given in Fig. 1. Ignition occurring, piston and cylinder move in opposite directions, the explosive effect acting on each. Piston B¹ causes crank B³ to move downward, while cylinder A causes cranks A⁸, A⁸, to move upward. The power effect is therefore evenly divided and at opposite 75 points of stroke, a perfect balancing effect being obtained. At end of outstroke exhaust valve C² opens and on return stroke the burnt charge is exhausted and driven out by the movement of piston B¹ and cylinder A. On next outstroke valve C² closes and valve C¹ opens, an explosive charge entering the cylinder A through tubes B⁵, B⁷. On the succeeding stroke this charge is compressed by the relative movements of cylinder and piston. Explosion takes place as the cranks pass over the dead centers, on the crank circle. It will be noted that check valve C cuts off access to tubes B⁵, B⁷, during compression and explosion, but exhaust tubes B⁶, B⁸ are controlled by the operable valve C² only.

In Fig. 2 I show an application of my improvement to a two cycle engine. In this the fuel mixture enters by a tube D, 100 jointed and slidable over another D¹, and exhaust takes place through jointed and slid- 105 able tubes D², D³. The necessary intake valve is not shown.

In Fig. 3 I show a further modification 105 of my improvement. In this I interpose between a movable piston E and the head of a movable cylinder E¹ a floating head, E², loosely fitted in cylinder. This head, E², Fig. 3, has lugs, E³, E³, on each end 110

that act as spacing bars, and prevent the head from seating on the end of the piston, or on the head of the cylinder E¹. Ignition plugs E⁴, E⁵ are inserted, one on each side of floating head, E². Through this head there is a hole, E⁶, of relatively small diameter.

The purpose of the head E² is to insure perfect ignition and at the same time 10 to keep the pressure on both movable bodies equal during firing. Thus it can be seen that if an imperfect charge is taken in one side of the head E² and fails to be fired by its spark plug, the head E² will 15 hold the compression on this side a sufficient length of time to permit the same to be fired by the hot flame from the exploding chamber entering through the hole E⁶ even if the charge is weak. If this head E² were 20 omitted and an imperfect charge was taken in, the same would not be exploded even if the two spark plugs were provided. The hole E⁶ is made relatively small to prevent a sufficient portion of the perfect charge 25 from leaking through to the chamber having the imperfect charge during the time required for compression and firing thereof.

In Fig. 4 I show a stationary cylinder 30 and two movable pistons, the combustion space divided by a floating head, E², Fig. 4, similar, in all respects to that just described except for the absence of lugs, E³, E⁸. Instead, I provide a movement limiting means consisting of an enlarged diameter of head (E²) fitting in a counterbored space, F. In this the head is limited 35 by shoulders at each end of counterbore, as shown.

Although the specification describes an

internal combustion engine it is evident that 40 the structure shown would be operative with either steam or air.

What I believe is new and ask to have protected by Letters Patent is—

1. In an engine, a pair of movable bodies, 45 a floating head arranged between the movable bodies, means for introducing a combustible mixture on each side of the head, and ignition means arranged on each side of the head, said head having a relatively 50 small port extending therethrough.

2. In an engine, a pair of movable bodies, a movable head between the bodies having a relatively small port therethrough, means for introducing a combustible mixture on 55 each side of the head, and means for limiting the movement of the head to hold the same in spaced relation to said bodies.

3. In an internal combustion engine, a 60 reciprocating cylinder, a piston mounted for reciprocating movement in the cylinder, a movable head arranged intermediate the head of the cylinder and the piston, a spark plug carried by the cylinder positioned on one side of the head, a spark 65 plug carried by the piston and arranged on the other side of the head, a pair of exhaust and inlet pipes positioned on opposite sides of the head, pipes carried by 70 the piston and cylinder slidably engaging the exhaust and inlet pipes, the head having a relatively small port extending therethrough, and spacing pins carried by the 75 opposite faces of the head for engaging the piston and cylinder head.

In testimony whereof I affix my signature.

ALVAH L. POWELL.
